ABSTRACT

A molded plastic two-part drawer front includes a first portion forming the exterior of the drawer from which may be molded to simulate carved decorations and a section portion forming the inner surface of the drawer front and incorporating dove-tailed slots formed vertically therein and a horizontal groove interconnecting said slots for the reception of dove-tailed ends of drawer side pieces and the forward edge of the drawer bottom respectively. The dove-tailed ends of the drawer side pieces are adapted to slide vertically into the dove-tailed slots in the second position so as to secure the drawer side portions to the composite drawer front.

MOLDED TWO-PART DRAWER FRONT

This application is a continuation of application Ser. No. 198,231, filed Nov. 11, 1971, and now abandoned.

BACKGROUND OF THE INVENTION

1. Field of the Invention

This invention relates to furniture and more particularly to drawer constructions and still more particularly to the drawer fronts used in such drawer constructions and wherein molded plastic pieces may be used to form the same.

2. Description of the Prior Art

Prior structures of this type include the conventional wooden drawer construction wherein the front of the drawer is a wooden piece having dove-tailed grooves formed on its inner surface for slidably receiving and retaining the dove-tailed ends of the drawer sides of the drawer. Molded plastic drawer front portions have been added to the wooden drawer front pieces for providing an improved decorative characteristic to the drawer front as such molded pieces may closely resemble carved wood. In the prior art structures the molded front portions of the drawers have been secured to the wooden front pieces of the drawers by fasteners as known in the art.

SUMMARY OF THE INVENTION

A molded two-part drawer front in which both parts are capable of being molded by injection molding techniques wherein the two-parts when assembled form a complete drawer front capable of receiving the forward dove-tailed ends of the drawer sides as well as the forward end of the drawer bottom and eliminating the need of the wooden drawer front portion heretofor believed necessary.

DESCRIPTION OF THE DRAWINGS

FIG. 1 is an exploded perspective view with parts broken away and parts in cross section illustrating the molded two-part drawer front and portions of the drawer sides and bottom.

FIG. 2 is a horizontal section through the molded two-part drawer front when assembled with parts broken away and illustrating the forward ends of the drawer sides and the forward portion of the drawer bottom assembled thereto.

DESCRIPTION OF THE PREFERRED EMBODIMENT

In the embodiment chosen for illustration, the molded two-part drawer front comprises a exterior front portion 10 having top, bottom, and side walls 11, 12, 13 and 14 respectively formed at right angles thereto and the outer edges of which are provided with a continuous shoulder 15 therealong. The outward portion of the exterior front portion 10 of the drawer may be obviously molded in any desired configuration. The inner portion of the exterior front portion 10 of the drawer front is provided with spaced vertical walls 16 and 17 respectively which walls are spaced inwardly from the end walls 13 and 14 heretofor referred to, notches 18 and 19 are formed in the bottom wall 12 between each of the pairs of walls 16 and 17 respectively. A second or inner portion 20 of the molded two-part drawer front is generally rectangular and conforms in overall shape and thickness with the shoulder 15 heretofor referred to so that the same can be nested there-

against and cemented thereto as well as to the outermost narrow edges of the walls 16 and 17 of the exterior front portion 10. Vertical slots 21 and 22 are formed in the second or inner portion 20 of the molded two-part drawer front and vertical ribs 23 and 24 respectively are formed on the innermost surface of the second or inner portion 20 for registry between the pairs of vertical walls 16 and 17 respectively and as best seen in FIG. 2 of the drawings. The opposed surfaces of the ribs 23 and 24 are formed on angles so as to resemble dove-tailed channels and so as to be capable of receiving the dove-tailed ends 25 of drawer side pieces 26.

A horizontal groove is formed in the inner surface of the second or inner portion 20 of the molded two-part drawer front and extends between the dove-tailed shaped slots 21 and 22 and is adapted to receive the forward narrowed edge of a drawer bottom 28.

It will occur to those skilled in the art that the exterior front portion 10 and the second or inner portion 20 of the molded two-piece drawer front can be molded by conventional injection molding machines and with multiple cavity molds so that the parts can be economically produced. The drawer sides 26 and drawer bottom 28 heretofor referred to, may be formed of wood as in conventional drawer construction with the forward ends 25 of the drawer sides 26 being dove-tailed as also customary. The dove-tailed slots 21 and 22 formed in the second or inner portion 20 receive and retain the dove-tailed ends 25 of the drawer sides 26 and at the same time are capable of being formed in multiple cavity molds in an injection molding operation.

It will thus be seen that a molded two-part drawer front has been disclosed which may be economically and rapidly produced with any desired exterior configuration or design, and that it can be assembled so as to enable a wooden drawer bottom and wooden drawer sides to be assembled thereto in the conventional manner and thus result in a practical, inexpensive, and attractive drawer construction suitable for use in various furniture pieces and the like.

Although but one embodiment of the present invention has been illustrated and described it will be apparent to those skilled in the art that various changes and modifications may be made therein without departing from the spirit of the invention.

I claim:

1. A drawer front made of two plastic pieces for assembly to drawer sides having dove-tailed end portions, said drawer front consisting of a separately molded exterior piece and a separately molded inner piece arranged to be attached to one another, said inner piece having narrow vertical apertures formed therein with the walls of said inner piece defining said apertures being oppositely inclined with respect to one another so as to form open bottom dove-tailed configurations for the reception of the dove-tailed end portions of said drawer sides, ribs formed on said inner piece alongside said narrow apertures for increasing the thickness of said inner piece adjacent said apertures and increasing the depth of said apertures.

2. The drawer front of claim 1 and wherein said two plastic pieces are attached to one another.

3. The drawer front set forth in claim 1 and wherein a horizontal groove is formed in said inner piece between said narrow apertures for the reception of the

front edge of a drawer bottom positioned between said drawer sides.

4. The drawer front set forth in claim 1 and wherein said inner piece has a top edge and a bottom edge and said narrow apertures terminate inwardly of said top edge and extend through said bottom edge.

5. A drawer front made of two plastic pieces for assembly to drawer sides having dove-tailed end portions, said drawer front consisting of a separately molded exterior piece and a separately molded inner piece arranged to be attached to one another, said inner piece having narrow vertical apertures formed therein with the walls of said inner piece defining said apertures being oppositely inclined with respect to one another so as to form open bottom dove-tailed configurations for the reception of the dove-tailed end portions of said drawer sides, spaced vertical walls positioned in said exterior piece for engagement against said inner piece on either side of said narrow apertures formed therein.

6. A drawer front made of two plastic pieces for assembly to drawer sides having dove-tailed end portions, said drawer front consisting of a separately molded exterior piece and a separately molded inner piece arranged to be attached to one another, said inner piece having narrow vertical apertures formed therein with the walls of said inner piece defining said apertures being oppositely inclined with respect to one another so as to form open bottom dove-tailed configurations for the reception of the dove-tailed end portions of said drawer sides, right angular top, bottom and side wall extensions on said exterior piece, a continuous shoulder being formed around the inner edges of said extensions, the inner piece being of a size and shape for registry on said continuous shoulder of said extensions.

7. A drawer front made of two plastic pieces for assembly to drawer sides having dove-tailed end portions, said drawer front consisting of a separately molded exterior piece and a separately molded inner piece arranged to be attached to one another, said inner piece having narrow vertical apertures formed therein with the walls of said inner piece defining said apertures being oppositely inclined with respect to one another so as to form open bottom dove-tailed configurations for the reception of the dove-tailed end portions of said drawer sides, ribs formed on said inner piece alongside said narrow apertures for increasing the thickness of said inner piece adjacent said apertures and increasing the depth of said apertures and wherein the exterior

piece has spaced, vertical walls positioned therein for engagement against the inner piece on either side of said apertures.

8. A drawer front made of two plastic pieces for assembly to drawer sides having dove-tailed end portions, said drawer front consisting of a separately molded exterior piece and a separately molded inner piece arranged to be attached to one another, said inner piece having narrow vertical apertures formed therein with the walls of said inner piece defining said apertures being oppositely inclined with respect to one another so as to form open bottom dove-tailed configurations for the reception of the dove-tailed end portions of said drawer sides, ribs formed on said inner piece alongside said narrow apertures for increasing the thickness of said inner piece adjacent said apertures and increasing the depth of said apertures and wherein the exterior piece has spaced members positioned therein for engagement against said ribs.

9. In a drawer assembly having a front panel and sides and a bottom joined to the front panel: the improvements in which said sides have continuous dove-tail tenons thereon, said front panel has dove-tail slots therein to receive and interlock with said dove-tail tenons; and said front panel has a plain slot extending between said dove-tail slots in position to receive said bottom along a margin thereof, said front panel further being comprised of separately formed pieces, means aligning said shells in assembling and cooperating means in said pieces forming said dove-tail slots upon assembly of said pieces.

10. In a drawer front panel the improvement consisting of a first body forming the exposed front of the drawer panel and a second body forming the interior of the drawer panel, said first body being formed with an inner-continuous surface having flanges bounding its periphery, said flanges all being on the same side of said surface; said second body being sized to fit with and be aligned by said flanges on said first body; and means on said bodies including projections selectively distributed over said inner surface on said first body and cooperating projections distributed over said second body in positions within the bounds of said flanges to be engaged by said first mentioned projections, certain of said projections being elongated and arranged in spaced relation to constitute dove-tail slots opening through said second body.
